DESCRIPTION

FIG. 1 is a top, front, right side perspective view of a first embodiment of a frame subassembly of a patient transport apparatus;

FIG. 2 is a bottom, rear, left side perspective view of the frame subassembly of a patient transport apparatus of FIG. 1;

FIG. 3 is a front view of the frame subassembly of a patient transport apparatus of FIG. 1;

FIG. 4 is a top view of the frame subassembly of a patient transport apparatus of FIG. 1;

FIG. 5 is a bottom view of the frame subassembly of a patient transport apparatus of FIG. 1;

FIG. 6 is a right side view of the frame subassembly of a patient transport apparatus of FIG. 1;

FIG. 7 is a left side view of the frame subassembly of a patient transport apparatus of FIG. 1;

FIG. 8 is a rear view of the frame subassembly of a patient transport apparatus of FIG. 1;

FIG. 9 is a top, front, right side perspective view of a second embodiment of a frame subassembly of a patient transport apparatus;

FIG. 10 is a bottom, rear, left side perspective view of the frame subassembly of a patient transport apparatus of FIG. 9;

FIG. 11 is a front view of the frame subassembly of a patient transport apparatus of FIG. 9;

FIG. 12 is a top view of the frame subassembly of a patient transport apparatus of FIG. 9;

FIG. 13 is a bottom view of the frame subassembly of a patient transport apparatus of FIG. 9;

FIG. 14 is a right side view of the frame subassembly of a patient transport apparatus of FIG. 9;

FIG. 15 is a left side view of the frame subassembly of a patient transport apparatus of FIG. 9; and,

FIG. 16 is a rear view of the frame subassembly of a patient transport apparatus of FIG. 9.

In the drawings, the broken lines represent unclaimed portions of the frame subassembly of a patient transport apparatus and form no part of the claimed design.
